CLAIM

I claim the ornamental design of a bean bag toss game having an illuminatable memo board, as shown and described.

DESCRIPTION

FIG. 1 is an upper perspective view of a bean bag toss game having an illuminatable memo board.

FIG. 2 is a top plan view of the bean bag toss game having an illuminatable memo board of FIG. 1, oriented as if resting on a horizontal surface.

FIG. 3 is a bottom plan view of the bean bag toss game having an illuminatable memo board of FIG. 2.

FIG. 4 is a left side elevation view of the bean bag toss game having an illuminatable memo board of FIG. 2.

FIG. 5 is a right side elevation view of the bean bag toss game having an illuminatable memo board of FIG. 1, oriented as if resting in a vertical position.

FIG. 6 is a front side elevation view of the bean bag toss game having an illuminatable memo board of FIG. 2; and, FIG. 7 is a rear side elevation view of the bean bag toss game having an illuminatable memo board of FIG. 2.

The evenly dashed broken lines depict features of the bean bag toss game having an illuminatable memo board that form no part of the claim. The dash-dot lines illustrate the bounds of the claim and form no part of the claimed design.
